UNITED STATES PATENT OFFICE.

WILLIAM RIMKE, OF BERWYN, ILLINOIS.

PORTABLE TALKING-MACHINE CASE.

Application filed September 1, 1923. Serial No. 680,569.

To all whom it may concern:

Be it known that I, WILLIAM RIMKE, a citizen of the United States, residing at Berwyn, in the county of Cook and State of Illinois, have invented new and useful Improvements in Portable Talking-Machine Cases, of which the following is a specification.

This invention relates to cases or cabinets for talking machines, though adapted for other purposes, and has for its object the provision of a novel case designed to contain a talking machine mechanical unit, the case being so constructed and arranged that it may be folded and locked for convenience in transportation for use of the talking machine at picnics, in camps, on tours and the like, the case being moreover of such formation that by removing certain portions thereof it may be installed within a cabinet so that the device will then constitute a well known type of talking machine suitable for household use.

In my co-pending applications numbers 447,960 filed February 26th, 1921, and allowed February 13, 1923; 466,563 filed May 3rd, 1921; 502,893, filed September 24th, 1921; and 609,264 filed December 27th, 1922, I have shown talking machine cabinets including skeleton frames having panels which may or may not be removable, and in one of the applications I have shown a desk like device, all the applications, however, showing cabinets within which is mounted a talking machine unit which is capable of being removed to serve as a portable machine.

The essential object of the present invention is the provision of a case in which the cover is removably hingedly mounted and is furthermore equipped with peculiar fastening means, and in which the top and one end are removable to permit installation of the unit within a regular cabinet, the arrangement being such that all the parts are held locked by a single lock.

An additional object is the provision of a device of this character which will be simple and inexpensive in manufacture, highly efficient in use, durable in service and a general improvement in the art.

With the above and other objects and advantages in view the invention consists in the details of construction to be hereinafter more fully described and claimed and illus-

trated in the accompanying drawings, in which:

Figure 1 is a perspective view of the device in closed position,

Figure 2 is a plan view thereof in open position,

Figure 3 is a front elevation with the end member removed,

Figure 4 is a longitudinal section showing the means for holding the cover latched,

Figure 5 is a cross section through the latching means and showing the cover closed,

Figure 6 is a perspective view of a type of cabinet in which the device may be mounted,

Figure 7 is a plan view with the motor board removed to disclose the interior mechanism and to show the tone arm stored within the interior,

Figures 8 and 9 are detail views.

Referring more particularly to the drawings I have shown the device as comprising a rectangular box like casing 10 including a bottom 11, sides 12 and a closed end 13. Secured at the top of the sides 12 at the open end of the casing and fitting within rabbets 14 in the sides is one section 15 of the top, and located contiguous to this section is the motor board 16 which is removable and which carries the motor indicated roughly at 17. It makes no difference whether this motor be of the electric or spring type as either might be used. This motor board is held in position by screws 18 which may be removed in case it is necessary to have access to the motor for the purpose of making repairs. Secured within the rabbets at the rear or closed end wall is a top section 19 formed with an opening 20 through which passes the tone arm 21, the tone arm being equipped with the usual reproducer 22 which is also removable. The space between the section 19 and the motor board is adapted to be closed by a removable section 23 whose edges are accommodated in grooves 23' in the parts 12 and 13.

Located within this box or casing is the amplifying horn 26 which includes rearwardly converging sides 27 leading to a throat 28 which is curved upwardly as shown and which communicates with the opening 20 in the top. Between the sides 27 of this horn and the sides 12 of the box are spaces 29

either or both of which may be used for storage purposes, one receiving the tone arm and the other receiving the reproducer, when these elements are disconnected for rendering the device portable.

Mounted at the closed end of the casing is the cover 30 which is of a size and shape to have its edges bear upon the upper edges of the sides 12 and the end portions of the 10 sections which constitute the top. This cover is mounted by hinges each including two leaves 31 having the usual knuckles 32 through which pass removable pintles 33 which may be disengaged for effecting removal of the cover. These pintles are formed at one end with lateral extensions 34 constituting handles whereby they may be easily grasped when effecting removal.

For holding the cover closed, I provide a 20 pair of catches 35 pivoted at 36 within the cover and adapted to pass through slots 37 in the front section 15 of the top and to be engaged with studs 38 which project toward each other from the sides 12 below 25 the slots 37. Extending from side to side is a partition 39 arranged below the studs and supporting a removable drawer 40 provided for the purpose of holding a brush or any small tools which might be needed for 30 use in connection with the machine. When this drawer is in place it prevents the catches 35 from being disengaged from the studs 38. The drawer is equipped with suitable finger holes 41 and may also be provided with a 35 frame 42 within which may be inserted an advertising card or a card bearing the name and address of the owner or in fact any other matter.

For locking the entire device closed, I 40 provide an end member 43 equipped at its lower edge with dowels 44 received within sockets 45 in the forwardly projecting edge or end of the bottom 11. A suitable lock device 46 is mortised into the rear side of 45 this end member at the upper edge thereof and has a movable bolt 47 projectable into engagement with a keeper recess 48 in the cover. One side of the casing or box carries a pivoted handle 49 which is adapted to be 50 folded down into a correspondingly shaped recess 50.

When the device is to be used as a portable talking machine, the lock 46 is unlocked, the end member 43 is removed, the cover is 55 swung open, the removable section 23 is removed and the turn table and reproducer together with the tone arm are removed from the storage compartment within the

device and are properly assembled as shown, the turn table being engaged upon the 60 spindle of the motor. The device is then ready for use. By disassembling these parts and restoring them to the positions originally disclosed, the device is ready for transportation and may be carried about easily 65 by means of the handle 49, all the parts being adequately protected. It might be mentioned in passing that the rear section of the top 19 carries a block 51 recessed out to contain the needle to be used in playing and 70 this block is engaged by the rear or hinged end of the cover when the cover is closed and consequently acts as a reinforcement.

When the device is to be installed in the regular or large cabinet to constitute the 75 mechanical unit, the end member 43 is removed, the cover is swung open and removed by pulling out the pintles 33, and the handle 49 is swung down into the recess 50 which receives it. The device is then inserted with 80 in the compartment disclosed in the large cabinet and when the panels thereof are placed in position the completed device will have the same appearance as an ordinary 85 talking machine and will be neat and attractive without their being any suggestion of the unit being removable to constitute a portable instrument.

While I have shown and described the preferred embodiment of my invention it 90 is of course to be understood that I reserve the right to make such changes in the form, construction and arrangement of parts as will not depart from the spirit of the invention or the scope of the subjoined claim. 95

Having thus described my invention I claim:

In a device of the character described, a rectangular box like receptacle having its bottom, both sides and one end closed and 100 its top and one end open, a plurality of sections secured upon the sides and constituting the top, one of said sections being temporarily secured whereby to be removable, a cover hinged upon said closed end and carrying pivoted catches, the forward section of the top being slotted for the reception of said catches, retaining studs projecting inwardly from the sides below said slots and with which said catches engage, 105 and a removable member for closing the open end equipped with locking means engaging said cover.

In testimony whereof I affix my signature.

WILLIAM RIMKE.
